CONCENTRATION OF ORES

Charles T. Morrison and Harry T. Eastman,
Chicago, Ill.

Application July 27, 1935, Serial No. 33,484

7 Claims. (Cl. 209—477)

This invention relates to the concentration of ores and particularly to the concentration of placer ores which contain metallic particles or metalliferous particles of substantially greater specific gravity than the gangue with which they are associated. The invention is, however, not limited to its application to placer ores since it may be applied to ores which are ground or comminuted so as to liberate metallic or metalliferous particles of greater specific gravity than the associated gangue.

One of the objects of the present invention is to provide a method of concentrating ore which can be operated without the use of water, yielding the valuable ore content in highly concentrated form by the aid of purely mechanical operations.

A further object of the invention is to provide a purely vibratory method of concentrating ores.

A further object of the invention is to provide an inexpensive and effective apparatus for the concentration of ores in accordance with such methods.

Other objects, advantages and capabilities of the invention will appear from the following description of the method and apparatus in which it may be practiced, taken in conjunction with the accompanying drawings which illustrate such an apparatus.

In the drawings:

Figure 1 is a plan view of the apparatus.

Fig. 2 is a sectional elevational view therethrough, taken on the line 2—2 of Fig. 1;

Fig. 3 is an elevational view of the apparatus;

Fig. 4 is a sectional elevational detail view, taken on the line 4—4 of Fig. 5 showing the manner in which a hammer is mounted;

Fig. 5 is a sectional plan detail view;

Fig. 6 is a sectional detail view, taken on the line 6—6 of Fig. 5, and

Fig. 7 is a sectional detail view showing the closure of the hopper in a manner similar to Fig. 2, but on a substantially larger scale.

Referring to the drawings, the reference numeral 10 designates a hopper comprising four vertical sides 11 and four sloping bottom plates 12 which converge to a rectangular or square opening 13. The hopper is supported upon long skids 14 which enable it to be transported from place to place as the work progresses.

Four legs 15 are secured to the skids 14 and serve to support the hopper 10 at an elevated position. The legs 15 are preferably located at the corners of the hopper and project through the bottom of the hopper and terminate at an intermediate height on the sides 11. These legs

may be of any suitable shape and are surmounted by inclined plates 16 which guide material resting thereon downwardly towards the bottom of the hopper. The legs 15 are preferably bolted or tied through the side walls 11 to channel members 17 which are arranged around the exterior of the sides 11 at the lower end thereof. The upper edges of the walls 11 are reinforced by angle irons 18, which are best shown in Figs. 1 and 2. The whole structure is braced by diagonal tie rods 19 which are located immediately below the sides 11 and are connected to the legs 15, as best shown in Fig. 3.

The opening 13 is closed by a hopper-like door 20 which corresponds to the shape of the opening 13. This door is preferably mounted by means of hinges 21 upon one of the bottom sections 12. It may be secured in closed position by means of a bolt or pin 22. As best shown in Fig. 7, the bottom sections 12 overlap the adjacent sections 20 of the hopper-like closure 20 so that no pocket is formed and no impediment to the free descent of the heavy metal or metalliferous particles is presented at the points of contact of the closure 20 with the hopper 10. At its center, and consequently at its lowest point, the closure 20 is provided with a relatively small threaded outlet 23. This outlet may be mounted on the closure 20 by means of flanges 24 which underlie the wall portions of the closure 20.

The outlet 23 is normally closed by means of a threaded plug 25. The threaded portions of the outlet 23 and the plug 25 are cut away at intervals around the circumference, as indicated at 26, so that the plug may be securely mounted 35 in position by mere insertion and turning through a fraction of a revolution, after the manner common in the case of breech blocks of large guns. The material to be treated in the hopper may be supplied thereto in any suitable way. It is preferred, however, to supply this material by means of an overhead conveyor 27 which may suitably extend over a battery of apparatus of the type just described. A baffle 28 suitably located above the hopper 10 causes the material to be delivered from the conveyor 27 into the hopper. As will hereinafter be more fully described, the valuable, highly concentrated fraction of the ore moves gradually downward and finally rests immediately above the plug 25 or in close proximity thereto. Consequently, by merely removing the plug 25 practically all of the valuable concentrate passes downwardly through the outlet 23 into a suitable reservoir held in position to receive same. After the concentrate has thus been 55

removed, the closure 20 is opened and the remaining contents of the hopper are discharged. They may suitably be deposited upon a conveyor 29 and removed to a suitable place. It will 5 readily be understood that the conveyor 29 may extend below the openings 13 of a row of hoppers, just as the conveyor 27 is arranged to supply such row of hoppers.

The means whereby the highly effective state 10 of vibration of the hopper and its contents is created and maintained, will now be described. These means comprise air hammers 30 which are distributed on the underside of the bottom of the hopper 10. Each air hammer 30 is supported 15 from the bottom by means of an inverted tripod 31 which has three legs 32, as best shown in Figs. 4 and 5. The legs 32 may suitably be formed of angle iron and at their upper ends they are welded or otherwise suitably secured to plates 33, which plates are welded or otherwise suitably secured to the bottom plates 12 of the hopper. The legs 32 converge downwardly and their lower 20 extremities are turned inwardly and secured by welding or other suitable means to plates 34 which serve as supports for the base of the air hammers 30.

Shim plates 35 are preferably inserted between the plates 34 and the bases of the air hammers 30. Each air hammer 30, together with its shim 30 plate 35, is inserted in position, as shown in Fig. 4 and brought into contact with two fixed pins 36 which project upwardly from the plate 34. After the air hammer has been mounted in position, a securing pin 37 is screwed into an appropriate opening in the plate 34 so that its upper 35 end projects into contact with the shim plate 35 and the base of the air hammer 30, as best seen in Fig. 6.

With reference to Fig. 5, it will be noted that 40 the two pins 36 and the pin 37 are located at equal distances with reference to the circumference of the air hammer 30 and shim plate 35. The upper end of the hammer 30 is inserted into a cup-like percussion abutment 38 which is invertedly mounted on the bottom plate 12 of the hopper. The percussion abutment 38 is provided with a flat base which is secured by welding or other suitable manner to said bottom plate. The percussion abutment 38 is provided with a 45 horizontal surface which is adapted to receive the impacts of the percussion member 39 of the hammer 30. Immediately above each percussion member 38 is mounted a vertical bar 40, which may suitably be in the form of an angle iron. These bars are intended to serve as vibrating 50 prongs communicating the impacts applied by the hammers 30 to the abutment members 38, throughout the mass of the ore contained in the hopper. The angle irons 40 have their angles 55 directed upwardly, relative to the slope of the bottom plates 12, so that they form no pockets in which ore might collect.

The hammers 30 are supplied with compressed air by means of flexible pipes 41 which are connected to main supply pipe 42. It will readily be understood that when air is supplied by the pipe 42, each air hammer is automatically set into rapid and violent operation. These hammers, together with the prongs 40, are distributed over 60 the bottom plates 12 in the manner best seen in Fig. 1 so that every portion of the charge of ore within the hopper is subjected to vibration.

The present method is based upon our discovery that placer ores and also ground or pulverized ores, which contain metallic or metal-

liferous particles of higher specific gravity than the associated gangue, can be classified and concentrated without the aid of water by merely maintaining them in a highly effective state of rapid vibration. We have found that the high speed vibrations engendered by the impacts caused by air hammers of well known and conventional type are highly effective for this purpose and cause the heavy metallic or metalliferous particles to descend through the body 10 of ore towards the lower portion thereof. If the vibratory process is continued for a sufficient period of time practically all the heavy metallic and metalliferous particles will work their way to the bottom of the mass.

The period of time during which the violent and rapid vibration must be maintained depends upon many factors such as the nature of the concentrate, the degree of concentration, the size of the hopper, and so forth. In the case of placer ores using the number of hammers shown in the drawings and with a hopper of side length of about eighteen feet, a highly satisfactory concentration of placer ores can be effected between one-half and two hours. At the end of the treatment the greater part of the gold contained in the placer ore will be located at or near the outlet 23. The plug 25 is removed and about two bushels of ore is permitted to pass through the outlet 23 into a suitable receptacle. This material contains 30 practically all the concentrate and it may be further concentrated in any desired manner.

In practicing the invention on a commercial scale, it is preferred to have a row of hoppers of the general type described above, all supplied by an upper conveyor 27. The movable baffle 28 enables the supply of ore to be diverted into any one hopper. After the hopper is filled, the hammers are started and the dry gravity concentration is conducted for the appropriate length of 40 time. After the concentrated ore is removed in the manner previously described, the closure 20 is opened and the remainder of the charge is permitted to pass on to the conveyor 29 which removes it to a suitable dumping place.

During the operation of our method the whole body of the ore appears to be in a state of violent vibration. The particles move or dance individually and the movement can be felt by the hand. During the vibratory movements of the individual particles, the heavy gold-bearing and other metallic and metalliferous particles seem to move forward to a greater extent than do the contiguous gangue particles. This operation appears to be repeated indefinitely during the application of the violent impacts which cause the individual particles of the ore to separate sufficiently to permit independent movement of the particles.

It will be noted that our improved method is 60 conducted without the aid of water and that it provides a highly effective method for concentrating placer deposits which occur in desert country. Many such deposits have a small gold content and cannot be treated by existing methods on a commercial basis because of the lack 65 of water on the one hand and the cost of transportation on the other hand. Our improved method permits such deposits to be treated in situ, yielding high value concentrates which can be further concentrated on the location or be 70 transported to more suitable locations for recovery of the gold or other valuable metals.

Although the invention has been disclosed in connection with the specific details of a preferred embodiment thereof, it must be under-

stood that such details are not intended to be limitative of the invention except in so far as set forth in the accompanying claims.

Having thus described our invention, what we claim as new and desire to secure by Letters Patent of the United States is:

1. An apparatus for concentrating ores comprising a hopper having a bottom converging downwardly toward its center, a door at the center of said bottom, an outlet mounted in said door, a plug closing said opening, a plurality of air hammers adapted to impact against the bottom of said hopper, inverted tripods secured to said bottom and supporting said hammers, and prongs mounted on the upper side of said bottom in alignment with said hammers.

2. The method of concentrating dry ore which comprises maintaining a body of dry ore particles in the form of an inverted cone, subjecting said body to high speed vibrations in the vertical direction, said vibrations being of such intensity and rapidity that the metalliferous particles are caused to descend through the body towards the lower apex of the conical body, and preventing currents of air through the body in the upward direction.

3. The method of concentrating dry ore which comprises maintaining a body of dry ore particles in the form of an inverted cone, applying rapidly repeated blows to said body and thereby establishing rapid vertical vibrations therein, said vibrations being of such intensity and rapidity that the heavy metalliferous particles are caused to descend towards the lower apex of the conical body and become concentrated thereat, and preventing upward currents of air through said body.

4. The method of concentrating dry ore which comprises placing said dry ore particles in a downwardly converging hopper, applying repeated impacts on said hopper to set the hopper and contents in a state of violent vibration in the vertical direction, maintaining said vibration

with intensity and rapidity and for sufficient time to cause the heavy metallic and metalliferous particles to descend towards the apical portion of the hopper, preventing upward currents of air through said ore particles, withdrawing a 5 concentrated fraction of ore, and thereafter withdrawing the remaining ore separate from said fraction.

5. An apparatus for concentrating ores comprising an imperforate downwardly converging 10 hopper having an outlet at its bottom, said hopper being adapted to retain a charge of ore for batch treatment, and mechanical means applying impacts to the hopper for maintaining said hopper and its contents in a state of vibration in the vertical direction of such speed and intensity that the heavy metalliferous particles are caused to descend through the ore to the lowermost end of the hopper adjacent said outlet. 15

6. An apparatus for concentrating dry ores comprising a hopper having an imperforate wall in direct contact with the ores to be concentrated, means for applying impacts to the imperforate hopper wall to cause vibrations in the 20 vertical direction of such speed and intensity that the heavy metalliferous particles are caused to descend through the ore, and means mounted on said wall and extending upwardly into the 25 ore space of the hopper for distributing said vibrations to the contents of the hopper. 30

7. An apparatus for concentrating ores comprising an imperforate hopper having a sloping bottom, means for applying vibrations to said hopper, means within said hopper for distributing said vibrations to the contents of the hopper, a door at the lowest portion of said bottom for emptying said hopper, an outlet mounted in said door for removing concentrate from said hopper, and a closure for said outlet. 35
